UNITED STATES PATENT OFFICE.

ELMORE D. SCARBOROUGH, OF CORSICANA, TEXAS.

SIGNAL APPARATUS FOR RAILWAYS AND HIGHWAYS.

Application filed November 19, 1926. Serial No. 149,287.

This invention relates to new and useful improvements in signal apparatus for installation at crossings of railways and intersecting highways and also at railway grade crossings, to warn drivers of vehicles and likewise the engineer of a railway locomotive, of an approaching train. The invention is also constructed and operatively arranged as to enable the engineer to be certain that the signals are in operation before the crossing point is reached on the occasion of both highway and railway crossings. The apparatus is also capable of utilization for street signaling.

15 The present invention is a continuation in part of an application for patent filed February 4, 1926, under Serial Number 85,912.

20 A particular object of the invention is to provide a signal apparatus of this nature having comparatively few parts and hence not susceptible of becoming inoperative and an apparatus which is economical of installation.

25 Having the above and other objects in view, the invention will be more clearly understood from a perusal of the following detailed description, taken in connection with the accompanying drawings and wherein:

30 Figure 1 is a plan view of a highway and railway crossing and illustrating an embodiment of the signal apparatus installed thereupon.

Figure 2 is a side elevational view of Figure 1, the view being taken along the center between the rails.

Figure 3 is a diagrammatic view illustrating the wiring arrangement.

40 Figure 4 is a vertical and longitudinal sectional view of the switch box, arm and signals.

Figure 5 is a vertical sectional view of a box containing the element for connecting the electrical circuit by the wheels of a locomotive or car.

45 Figure 6 is a view similar to Figure 5, taken along the line 6-6 of Figure 5.

Figures 7 and 8 are, respectively, an enlarged detail view and a cross-sectional view 50 of a dash-pot. Figure 8 being on line 8-8 of Figure 7.

Proceeding in accordance with the drawings, wherein numerals are employed to des-

ignate the various parts of the apparatus, 1 denotes one of the railway rails supported 55 upon the cross-ties 2-2 and 3 indicates the intersecting highway.

Referring to Figures 2 and 4, a switchbox is designated at 4 having a battery 4^a and provided with a door 4^b. The box has its top converging upwardly and provides an opening for threaded or other means of connection for a short length of pipe 5. The pipe 5 is connected by an elbow 6 to an overhanging tubular arm 7 and on this arm 60 is suspended by means of the short tubular member 8, a lamp body 9. The member 8 has an elbow and short nipple that screw in flange at the top of the lamp body. However, this form of construction may be varied and is only an instance of one mode 65 of construction thereof.

The lamp body 9 as will be apparent has four sides and on each of two of the sides directly opposite one another are two green 70 colored lenses 12-12. On each of the diametrically opposite sides of the lamp body are two similar lenses 13-13, colored red. On the overhanging arm is a bell 14. The globes 15 and the bell 14 are connected into 75 an electric circuit by the wires 16 and 17 and included in this same circuit is a time-recorder or time clock 14^a. The wires 16 and 17 are connected to each of the arms 18 of a switch and thence are connected to the 80 battery 4^a. The globes 15 are connected in the circuit by a lead wire 19 in a pipe 20 traversing the post 5 and arm 7 and directed into the lamp body 9. Connected to wire 16 is a lead wire 21 which is connected 85 to a solenoid 22. A wire 21^a forms the return wire for the lights and bell. In order to properly include the element located on the rail and which connects the circuit to

90 sound and display the signals as the locomotive or car rides over the rails 1, a wire 23 is connected to a plunger rod 24 and a wire 25 leading from the other post of the battery is connected to a contact 26. The lower end of the plunger 24 includes a wiper 95 or contact 27 and the contact 26 a wiper element 28.

Referring to Figure 5 it will be observed that the plunger 24 has a wheel-engaging head 29 and is seated in a box 30 which includes a covering 31. A collar 32 is ar- 100 105

2
ranged on the cover and includes a washer 33 as a means of protection against moisture, dust, or foreign elements entering the box. Attached to the under side of the cover is 5 an auxiliary box 34 and through which the plunger reciprocates. A spring 35, held in place by a pin 36 normally retracts the plunger after the circuit has been connected. The plunger has enough free movement to 10 permit lateral play as the wheel of the locomotive or car rides over the head 29.

Referring to Figure 7 also Figure 4, the solenoid has a reciprocating rod 38 and below the solenoid is a dash-pot 39.

15 Particular attention is directed to this dash-pot as it forms one of the main elements of the invention. This dash-pot is closed at top and bottom and is normally filled with oil. The rod 38 passes into the 20 dash-pot and is connected to a cup 40. The cup has a plurality of apertures 41 to allow free passage of oil and on the lower end which is open is a disk 42. This disk is loosely connected to the cup by two or more 25 pins or screws 43. Thus when the cup is moving up or down the disk will normally open or close the lower end of the cup.

The wall of this cup is drilled for a screw 44. The object of this screw is to limit the 30 upward movement of the cup to properly time the signals, as obviously the head of the screw when coming into contact with the cover of the dash-pot will stop the upward movement of the cup.

35 This arrangement will be better understood by reference to the switch arm 45. This arm carries an insulating plug 46 and operates to move apart the switch arms 18 on the downward movement of the rod 38. 40 Manifestly the time required to open or close the switch will depend upon the distance the cup moves—determined by the setting of the screw 44.

Now when a locomotive wheel or car 45 wheel rides upon the head of the plunger 24, the plunger will be depressed and tilted slightly causing the contacts 27 and 28 to wipe against each other thus connecting the circuit. The solenoid then draws upward 50 the rod 38, pulling the plug 46 out from between the switch points and closing the circuit. The bell will be sounded and the lights displayed, including the working of the clock, until the screw 44 strikes the top 55 of the cup, whereupon the cup will descend, open the switch arms 18 and break the circuit. As the cup rises the oil will pass through the apertures 41, the disk 42 being at the point shown in the drawing, Figure 7. 60 On descending the disk is forced against the mouth of the cup and the movement of the latter downward will be slow enough to permit the signals to sound and be displayed as a warning.

65 This arrangement is effective for trains

passing in either direction. After the locomotive has passed over the first plunger, on striking the opposite one the current is not affected, since the plunger on being depressed on its side opposite the contacts will 70 not open or close the circuit.

It should be understood that the plunger is adaptable to being placed on either side of a rail so that either the flange or tread of the wheel will depress the plunger. Also that 75 modifications may be made in the invention without departing from the spirit and meaning of the appended claims.

What is claimed is:

1. A signal apparatus comprising a mechanically operated switch adapted to be mounted adjacent a railway rail and operated by the wheel of a car passing along the rail, a circuit controlled by said switch including a solenoid, means for retarding the operation of said solenoid, and a second switch controlled by said solenoid having suitable signals in circuit therewith, said switch being normally open when the solenoid is inactive, but closed when the solenoid is actuated and maintained in closed position for a predetermined period of time by said retarding means, whereby the circuit is closed through said signal, and the signal operated during said predetermined period. 80

2. A signal apparatus for railways and highways comprising a mechanically actuated switch adapted to be mounted adjacent a railway rail and operated by the wheel of a car passing along the rail, a circuit controlled by said car operated switch including a solenoid, said solenoid having a rod extending from the core thereof, a retarding dash pot at one end of the rod, a switch controlled by said solenoid, having suitable signals in circuit therewith, said solenoid controlled switch comprising a pair of spring fingers tending to contact with each other, and an insulating plug carried by said solenoid rod normally holding said spring fingers apart when the solenoid is inactive, but being withdrawn when the solenoid is activated and maintained in withdrawn position for a determined period of time by the operation of said dash pot, whereby the circuit through said signal is closed and the signal operated during said predetermined period. 90

3. A signal apparatus for railways and highways comprising a mechanically actuated switch adapted to be mounted adjacent a railway, and operated by the wheel of a car passing along the railway, a circuit controlled by said car operated switch, and including visible and audible signals, and including a switch controlled by a solenoid, said circuit being normally inoperative, said solenoid controlled switch including a pair of spring contact fingers, said solenoid adapted to be energized when the car actu- 100

ated switch is operated, a rod carried by said solenoid having at one end a retarding dash pot, an arm connected to said rod, and an insulating plug carried by said rod adapted to normally engage and separate the spring fingers of said solenoid actuated switch, but adapted to be withdrawn when the solenoid

is activated, and to be maintained in withdrawn position for a determined time by said dash pot, whereby said spring contact 10 fingers are brought together and said signals operated.

In testimony whereof I affix my signature.

ELMORE D. SCARBOROUGH.
